CONTAINER CLOSURE

Filed March 13, 1928

Inventor
William H. Rose

By his Attorney
Frank Freeman

UNITED STATES PATENT OFFICE

WILLIAM H. ROSE, OF JERSEY CITY, NEW JERSEY

CONTAINER CLOSURE

Application filed March 13, 1928. Serial No. 261,259.

My invention relates to container closures and refers particularly to devices of this character having locking pronged tongues.

My device is adapted as a closure for annular containers, the side of which is capable of penetration by metal prongs carried by the closure.

Another object of my device is a closure which can be readily applied and readily removed from container attachment.

Another object of my device is an arrangement of locking prongs whereby the attachment of my device to a container will cause incisions within the side of the container of practically the same size as the prongs inserted therein.

Another object of my invention is a closure in which the tongues carrying the locking prongs will be maintained in abutment with the container side and protected against accidental displacement.

The above mentioned, and other, advantageous features of my device will be evident upon a consideration of my specification and its accompanying drawings.

My device in a general way comprises a central portion having a downwardly extended annular flange, preferably U-shaped carrying a plurality of spaced dependent tongues, the side of each tongue carrying a plurality of inwardly turned prongs.

Further, I prefer that each prong should be of such shape that the upper edge thereof will bear right angles to the edge of its tongue, and a consideration of the accompanying drawings will indicate the advantages of this particular formation of prong.

In operation, my device is placed upon, or over, the open end of a container, the flange abutting upon the upper outer face of the container side, and the tongues bent outwardly to free the prongs from contact with the container side. When the device is thus positioned the tongues are bent inwardly until they abut upon the outer face of the container side, the prongs being thus forced into the said side.

It is naturally advantageous that the prongs be retained as firmly as possible within the container side and this is best ac-

complished by having the incisions within the side the same size as the prongs therein.

A consideration of this locking movement will indicate that by having the upper edge of a prong at right angles to the edge of its tongue, this movement will move the upper edge of the prong in the arc of the circle of its tongue movement, thus causing the prong to enter the container side at a right angle thereto, thus producing an incision the size of the prong.

A further advantageous feature of prongs upon the sides of the tongues is that it binds the latter to the container side preventing accidental displacement.

In some modifications of my device I employ rods or bands encircling the tongues with means removably locking the band to the tongues to prevent accidental displacement of the device.

In the accompanying drawings illustrating modified forms of the device of my invention, similar parts are designated by similar numerals.

Figure 1 is a side view of a container with one form of my closure attached thereto.

Figure 2 is an enlarged side view of one of the tongues of Figure 1.

Figure 3 is a vertical cross-section of one tongue in unlocked position.

Figure 4 is a section through the line 4—4 of Figure 2 with the tongue in locked position.

Figure 5 is a vertical cross-section of a modified form of my device.

Figure 6 is a vertical cross-section of a modified form of my device.

Figure 7 is a vertical cross-section of a modified form of my device.

Figure 8 is a front view of a modified form of tongue and prongs.

Figure 9 is a section through the line 9—9 of Figure 8.

Figure 10 is a vertical cross-section of a modified form of my device.

The particular form of the device of my invention shown in Figures 1 to 4 inclusive of the accompanying drawings comprises the central annular member 12, having a U-shaped flange formed by the upwardly ex-

tended element 13, the horizontal element 14 and the downwardly extended element 15. The element 15 is extended into a plurality of spaced tongues 16, 16, the lower portion of each tongue being rolled outwardly and upwardly to form a hook-shaped holder 17 for the binding ring 18. Each side of each tongue 16 carries a plurality of inwardly extended prongs 19, 19, the upper edge face of each prong being at right angles to the face of the tongue. A projection 20 carried by each tongue 16 prevents the accidental upward movement of the binding ring 18.

The operation of my device is as follows:—

My device is placed upon the annular side 21 of a receptacle as shown in Figure 3, the tongues 16, 16, are then placed inwardly in the direction of the arrow of Figure 3, and the binding ring 18 then moved downwardly into position in the hooked member 17. The tongues 16, 16, may also be moved into locked position by moving the ring 18 downwardly over the extended tongues.

As the upper edges of the prongs 19, 19, are at right angles to the face of its tongue, these prongs will enter the receptacle side 21 at practically right angles and hence each incision made within the receptacle side will be of the exact size of its prong, which would not be the case if the prongs were positioned angularly otherwise, and this fitment of prong and incision insures a firmer locking engagement than is otherwise possible.

In the modification shown in Figure 5, the hooked member 22 is longer than the previously described hooked member 17, and hence, can be formed slightly around the ring 18 after the latter is in place thus obviating the necessity of the projection 20.

In the modification shown in Figure 6, the bar ring 18 is replaced by a band ring 23.

In the modification shown in Figure 7, the hooked member 17 of Figure 6 is replaced with a shoulder extension 24.

In the modification shown in Figures 8 and 9, each tongue 16 has an end prong 25 in addition to the side prongs 19, 19.

In the modification shown in Figure 10, the projection 20 of each tongue 16, is beneath the binding band 26 which has an annular groove 27 into which the projection 20 will be positioned when the band 26 is in locking position.

I do not limit myself to the particular size, shape, number or arrangement of parts as shown and described as these are given simply as a means for clearly describing the device of my invention.

What I claim is:—

1. In a container closure of sheet-material, in combination, a central portion adapted to cover the open portion of a container; a dependent peripheral flange carried by said central portion adapted to abut upon the sides of a container; a plurality of dependent

spaced tongues carried by said flange; a plurality of inwardly extended flat prongs carried by each side of said tongues, the plane of said tongues being angularly positioned to the plane of said central portion and parallel to the longitudinal axis of a container to which said device is attached, and means independent of said prongs preventing the vertical movement of said device when positioned upon a container.

2. In a container closure of sheet material, in combination, a central portion adapted to cover the open portion of a container; a dependent peripheral flange carried by said central portion adapted to abut upon the sides of a container; a plurality of dependent spaced tongues carried by said flange; a plurality of inwardly extended flat prongs carried by each side of said tongues, the plane of said tongues being angularly positioned to the plane of said central portion and parallel to the longitudinal axis of a container to which said device is attached, and a closed ring capable of downward movement over said tongues, such movement forcing the prongs into the side of a receptacle upon which the device is placed.

3. In a container closure of sheet material, in combination, a central portion adapted to cover the open portion of a container; a dependent U-shaped peripheral flange carried by said central portion adapted to abut upon the sides of a container; a plurality of dependent spaced tongues carried by said flange; a plurality of inwardly extended flat prongs carried by each side of said tongues, the plane of said tongues being angularly positioned to the plane of said central portion and parallel to the longitudinal axis of a container to which said device is attached, and means independent of said prongs preventing the vertical movement of said device when positioned upon a container.

4. In a container closure of sheet material, in combination, a central portion adapted to cover the open portion of a container; a dependent U-shaped peripheral flange carried by said central portion adapted to abut upon the sides of a container; a plurality of dependent spaced tongues carried by said flange; a plurality of inwardly extended flat prongs carried by each side of said tongues, the plane of said tongues being angularly positioned to the plane of said central portion and parallel to the longitudinal axis of a container to which said device is attached, and a closed ring capable of downward movement over said tongues, such movement forcing the prongs into the side of a receptacle upon which the device is placed.

5. In a container closure of sheet-material, in combination, a central portion adapted to cover the open portion of a container; a dependent peripheral flange carried by said central portion to abut upon the sides of a

container; a plurality of dependent spaced tongues carried by said flange; a plurality of inwardly extended flat-prongs carried by each side of said tongues, the plane of said 5 tongues being angularly positioned to the plane of said central portion and parallel to the longitudinal axis of a container to which said device is attached.

Signed at New York city, in the county 10 of New York and State of New York, this 12th day of March, 1928.

WILLIAM H. ROSE.
